(57) **CLAIM**

The ornamental design for a sight enhancer, as shown and described.

DESCRIPTION

FIG. 1 is an enlarged front perspective view of a sight enhancer showing my new design;

FIG. 2 is an enlarged rear perspective view of the sight enhancer shown in FIG. 1;

FIG. 3 is a top plan view of the sight enhancer shown in FIG. 1;

FIG. 4 is a rear elevational view of the sight enhancer shown in FIG. 1;

FIG. 5 is a right-side elevational view of the sight enhancer shown in FIG. 1 wherein the left side is a mirror image of the right side;

FIG. 6 is a front elevational view taken from FIG. 1; and, FIG. 7 is a bottom plan view of the sight enhancer shown in FIG. 1.

1 Claim, 2 Drawing Sheets
